UNITED STATES PATENT OFFICE.

FREDERICK MENZENHAUER, OF JERSEY CITY, NEW JERSEY, ASSIGNOR TO
MENZENHAUER & SCHMIDT, OF SAME PLACE.

MANDOLIN-CITHERN.

SPECIFICATION forming part of Letters Patent No. 651,195, dated June 5, 1900.

Application filed January 13, 1899. Serial No. 702,019. (No model.)

To all whom it may concern:

Be it known that I, FREDERICK MENZENHAUER, a citizen of the United States, residing at Jersey City, in the county of Hudson 5 and State of New Jersey, have invented certain new and useful Improvements in Mandolin-Citherns, of which the following is a specification.

This invention relates to improvements in 10 citherns or similar stringed instruments the strings of which are sounded by means of picks, so that a tremolo or mandolin effect is produced, the picks being actuated by means of keys depressed by the fingers of one hand, 15 while the other hand or a separate motor produces the power necessary to vibrate or rapidly reciprocate the entire pick-carrier, so that a tremolo or mandolin effect of the strings is produced.

20 The invention consists of novel features and parts and combinations of the same, as will be fully described hereinafter and then pointed out in the claims.

A practical embodiment of my invention 25 is represented in the accompanying drawings, forming a part of this specification, in which similar characters of reference indicate corresponding parts in all the views.

Figure 1 is a top view of my improved mandolin-cithern. Fig. 2 is a vertical transverse section of the same on line 22, Fig. 1, drawn on a larger scale. Fig. 3 is a vertical longitudinal section on line 33, Fig. 1, drawn on a still larger scale. Fig. 4 is a detail horizontal section 35 on line 44, Fig. 5, showing a portion of the mechanism for reciprocating the pick-carrier by hand. Fig. 5 is a vertical longitudinal section on line 55, Fig. 4; and Figs. 6 and 7 are respectively a detail vertical central section 40 and a bottom view of one of the pick-blocks.

Similar letters of reference indicate corresponding parts.

Referring to the drawings, A represents 45 the sounding-board, B the bottom, and C the outer strips, of the body of my improved cithern. The strings S are stretched in the usual manner over the scale-ribs r r', the scale-rib r being at the front end of the instrument and the scale-rib r' extending near the opposite or inclined end of the instrument. The front ends of the strings are at-

tached below the scale-rib r to pins s, while the opposite ends of the strings after passing the straining-pins s' on the scale-rib r' are applied to tuning-pins s². These parts may be arranged in any of the well-known ways, and the instrument may be of any desired form or size. Across the front portion of the instrument and transversely to the strings is 55 arranged a stationary keyboard D, which is supported at its ends beyond the strings on strips d, attached to the body of the instrument, and at its sides by longitudinal side walls d'. The keyboard D has a number of 60 holes in which are located keys D', having flanges k at their lower ends, said keys being preferably arranged in two rows vertically above the strings S. Below the keyboard is arranged a longitudinally - reciprocating pick-carrier E, which is supported 65 above the strings on antifriction-rollers e, one at each end of said carrier, said antifriction-rollers being supported on the sounding-board and provided at portions of their length 70 with sound-deadening tires e', of felt or other soft or elastic material. The motion of the antifriction-rollers e is limited by cushions d² and stop-pins d³, driven into the sounding-board, as shown in Fig. 2. Between the sides of the 75 pick-carrier E and the adjacent side walls d', supporting the keyboard are interposed strips d⁵ of felt or other suitable material, which are preferably attached to the side walls d', so as to prevent any noise that may be caused by 80 the reciprocating motion of the pick-carrier. The pick-carrier E is provided with a number of perforations, one below each key D', in which perforations are arranged vertically-movable pick-blocks e², which carry at their 85 lower ends shanks or picks e³, of steel, horn, hard rubber, or other suitable material, said picks extending through slots in the sheet-metal bottom plate e⁴ at the under side of the pick-carrier to a point just above the level of 90 the strings. Each pick-block e² is supported by a helical spring e⁵, which is interposed between the bottom of the block and the plate e⁴. The top of each pick-block is normally 95 below the level of the upper surface of the pick-carrier and is provided with two parallel ears e⁶, which serve to guide an antifriction-ball e⁷, upon which rests the lower end of the key D', which is located above the pick-block. 100

The distance between the upper surface of the pick-carrier E and the bottom surface of the key D' is less than the diameter of the antifriction-balls e⁵, so that the latter cannot escape from the recesses in the heads of the pick-blocks even when the instrument is placed in inclined or other position or jarred. The springs e⁵ of the pick-blocks serve to return the key-blocks and the keys into raised position after each depression and to retain them in this position, the upward movement of the keys D' being limited by their bottom flanges k.

The picks are attached centrally to the under side of the pick-blocks e² in such a manner that their flat sides are located parallel with the strings. The relative position of the picks to the strings S can be accurately adjusted so as to cause the even picking of the same even after the instrument has been in use for some time, by a set-screw o, the shank of which is screwed into the pick-block at a slight inclination toward the pick, so that the latter can be bent more or less by the head 25 of the screw, according as the same is screwed in more or less. This adjusting-screw forms an important feature of the present construction, as thereby the ready and reliable responding of the strings to the picks is secured when the instrument is first prepared for use, as well as when the same has been in use for some time and the picks require readjustment.

To the pick-carrier E is imparted a quick 35 longitudinally - reciprocating motion, either by a hand-crank, intermediate gearing, and a connecting-rod, as shown in Figs. 4 and 5, or by a spring or other motor M, as shown in Figs. 1 and 2. The hand-operated mechanism 40 consists of a friction-wheel b¹, the shaft b¹ of which is journaled in the block d⁴ and the keyboard D and which is turned by a crank b³, applied to its square projecting end. To the block d⁴ is pivoted at one end a link c¹, 45 which carries at its opposite end a smaller friction-wheel b⁴, which like the friction-wheel b is provided with a rubber or other frictional tire. To the projecting tongue b⁶ of the link c¹ is attached a helical spring b⁷, which is secured at its opposite end to the block d⁴ and 50 which serves to keep the friction-wheel b⁴ in contact with the friction-wheel b. A connecting-rod b⁸ is pivoted at one end to the pick-carrier E and at its opposite end to a wrist-pin b⁹ on the smaller friction-wheel b⁴. It is 55 obvious, however, that in place of the friction-wheels gear-wheel or any other motion-transmitting mechanism may be employed. The motor M consists of a power-spring, a 60 train of transmitting gear-wheels, a speed-regulating fly, and a connecting-rod by which the last pinion of the train is connected with the pick-carrier. These parts, with the exception of the spring, are indicated in dotted 65 lines in Fig. 1.

The operation of playing my improved

either will be readily understood from the drawings and the foregoing description. The mechanism for reciprocating the pick-carrier is preferably located at the left hand of the instrument. In this case the crank is turned by the left hand at a speed to produce the reciprocation of the pick-carrier at the proper speed. Each key is preferably numbered on the exposed upper surface or lettered to indicate the string or strings which will be sounded when a key or keys are depressed during the motion of the pick-carrier. The ears e⁶ of the pick-blocks e² are arranged at right angles to the plane of the picks, so that when the pick-carrier is reciprocated the antifriction-balls e⁷, rolling between the ears, have a tendency to keep them in the same direction as the pick-carrier, so that the picks are located with their flat sides toward the strings and bent as they engage them on the depression of the keys, so that the clear sounding of the strings is produced. It is expressly understood that the keyboard D carries a key for each pick-block, and as many of the latter are employed as there are strings S. One pick-block serves, however, to pick only one particular string and no other, and the stroke or throw given by the actuating mechanism to the pick-carrier is arranged accordingly—that is, when a key is pressed to move the corresponding pick-block into a lowermost active position then during the full stroke of the carrier in either direction only the corresponding string for the pressed key and pick-block is sounded. It is further understood that the under surface of the keys D is made sufficiently wide that it remains at all times in direct contact with the pick-block during the latter's travel with the pick-carrier, so that the pick-block is moved into active position whenever the corresponding key is pressed and no matter in what part of the stroke the pick-carrier is in at the time. Ordinarily the speed of the pick-carrier will be such that the strings will be sounded two or three times before the key is released, so that a continuous tremolo or a mandolin effect is produced as the piece of music is played. By turning the handle at varying speeds a varying degree of tremolo is obtained.

When a motor for reciprocating the pick-carrier is used, the motor-spring is wound up by a key applied to the arbor of the spring and the motor then started, so as to reciprocate the pick-carrier. The keys are depressed according to the piece to be played, so as to sound the strings, which, being repeatedly sounded in connection with the reciprocating pick-carrier, produce a tremolo or mandolin effect in playing. Besides the advantage of the uniform tremolo effect obtained both hands are free when a separate source of power is employed and may be used for depressing the keys, thus vastly increasing the number of strings which it is possible for the player to pick simultaneously.

Having thus described my invention, I claim as new and desire to secure by Letters Patent—

- 5 1. A stringed musical instrument, provided with a keyboard extending across the strings and having keys, a pick-carrier mounted to reciprocate across the strings, pick-blocks mounted on the said pick-carrier and standing normally above the strings and directly under and in direct contact with the keys of the keyboard, so that on pressing a key the corresponding pick-block is moved into a lowermost active position relatively to its string, and a mechanism for imparting a reciprocating movement to the said pick-board, to cause the active pick-block to sound its string, substantially as shown and described.
- 10 2. The combination, with the strings of a cithern or similar stringed instrument, of a keyboard extending across the strings and provided with perforations arranged relatively to the same, keys in said perforations, a pick-carrier guided below the keyboard and provided with perforations below the perforations of the same, spring-actuated pick-blocks located in the perforations of the pick-carrier, picks carried by said pick-blocks and extending to a point above the strings, antifriction-balls between the keys and pick-blocks, and means for reciprocating the pick-carrier, substantially as set forth.
- 15 3. The combination, with the strings of a cithern or similar stringed instrument, of a perforated keyboard extending transversely

of the strings, keys located in the perforations of the keyboard, a reciprocating pick-carrier, spring-actuated pick-blocks located in holes of said carrier, picks in said blocks, means for adjusting the picks relatively to the strings, and means for imparting reciprocating motion to the pick-carrier, substantially as set forth.

4. The combination, with the strings of a cithern or similar stringed instrument, of a keyboard extending across the strings, keys guided in holes of said keyboard, a pick-carrier below said keyboard, spring-actuated picks guided in holes of said carrier below the keys, and a motor for reciprocating said pick-carrier while the keys are depressed for sounding the strings, substantially as set forth.

5. In a cithern or other stringed instrument, a pick-block, provided at its under side with a pick, and means for laterally adjusting said pick relatively to said block, substantially as set forth.

6. In a cithern or other stringed instrument, a pick-block, provided with a pick at the under side, and a set-screw adjacent thereto for adjusting the position of the pick, substantially as set forth.

In testimony that I claim the foregoing as my invention I have signed my name in presence of two subscribing witnesses.

FREDERICK MENZENHAUER.
